(57) **CLAIM**

The ornamental design for a base station of cleaning machine, as shown and described.

DESCRIPTION

FIG. 1 is a front perspective view of a base station of cleaning machine showing our new design;

FIG. 2 is a front elevation view thereof;

FIG. 3 is a rear elevation view thereof;

FIG. 4 is a left side elevation view thereof;

FIG. 5 is a right side elevation view thereof;

FIG. 6 is a top plan view thereof;

FIG. 7 is a bottom plan view thereof; and,

FIG. 8 is a reference view thereof showing another state.

The dash-dash broken lines in the drawings depict the portions of the base station of cleaning machine which form no part of the claimed design.

1 Claim, 8 Drawing Sheets
